UNITED STATES PATENT OFFICE.

ISRAEL M. ROSE, OF NORWALK, CONNECTICUT.

IGNITING MECHANISM.

SPECIFICATION forming part of Letters Patent No. 242,373, dated May 31, 1881.

Application filed March 16, 1881. (No model.)

To all whom it may concern:

Be it known that I, ISRAEL M. ROSE, of Norwalk, in the county of Fairfield and State of Connecticut, have invented certain new and 5 useful Improvements in Igniting Mechanism, of which the following is a specification.

My invention relates to mechanism or apparatus in which a fulminate tape—that is, a strip of paper or other material provided with 10 pellets of ignitable material—is employed as a means of igniting; and an important object of the invention is to combine such an igniting mechanism with a kerosene-lamp burner, so that it will furnish a simple and very 15 desirable means for igniting the wick of the burner.

The invention consists in the combination of a rest, over which a tape provided with friction pellets of ignitable material may be drawn, 20 and a stationary igniter adjacent to the rest, and adapted to bear upon and serving to scratch and ignite the pellets on the tape as the latter is drawn past it.

The igniter consists of a spring-arm, which 25 is first deflected by the pellets and then springs back, thereby scratching over and igniting them.

The invention also consists in the combination, with a lamp-burner, of a rest adjacent to 30 the tip thereof, over which a tape provided with pellets of ignitable material may be drawn or moved, an igniter, and a standard or frame supporting said rest projecting upward within the cone of the burner, but isolated from and 35 independent of the wick-tube, and preferably forming a catch for holding the cone in place.

The invention also consists in the combination, with a lamp-burner, of a rest over which 40 a tape provided with pellets of ignitable material may be drawn or moved, adjacent to the tip of the wick-tube, an igniter, a magazine for a roll of tape attached to the exterior of the burner, and a reel or feed-spindle for drawing the tape from said magazine over the rest, and 45 for winding up the spent tape after its pellets have been consumed.

In the accompanying drawings, Figure 1 represents a vertical section of a lamp-burner having my improved igniting mechanism combined 50 with it, and Fig. 2 represents a plan thereof.

Similar letters of reference designate corresponding parts in both the figures.

A designates the base, B the wick-tube, and C the cone, of a kerosene-lamp burner of ordinary form.

55

D represents an upright standard, (shown as in the form of a tubular case,) attached at its lower end to the base A of the burner, and preferably made of sheet metal.

In the upper portion of the standard D is 60 pivoted a rotary drum or roller, E, over which a piece of tape, F, provided with pellets of material capable of ignition by friction, may be drawn or moved.

G designates a magazine, which is attached 65 to the exterior of the burner, (in this instance to the edge or circumference of the base A,) and which is adapted to receive a roll of the tape, as clearly shown in Fig. 1. From the magazine G the tape F is passed through a 70 hole in the base A within the cone C, thence upward within the standard D, over the rotary roller E, and down within the standard. The free end of the tape F is then secured to a feed-spindle or reel, H, which is journaled in 75 two cheek-pieces, a, with its axis parallel, or approximately parallel, with the axis of the circular magazine G; and it is obvious that by turning the feed-spindle or reel H the tape F may be drawn from the magazine G over the 80 rotary drum or roller E, and thence downward, and wound upon the reel or feed-spindle H.

As clearly shown in Fig. 1, the standard D projects upward within the cone C and close to the side thereof, but is wholly isolated from 85 and unattached to the wick-tube, so that oil cannot get upon the ignitable tape F and destroy the pellets. The upper end of the standard projects through an opening in the cone, which is formed by an extension of the cone-slit C'. 90

Upon the outer side of the standard D may be formed a shoulder, b, which bears upon the edge of the opening in the cone through which the standard D extends, as shown in Fig. 1, and thus forms a catch for holding the cone in 95 place upon the base A of the burner.

In lieu of the tubular standard D, the roller E might be pivoted in a standard consisting of a straight strip of metal. The roller E, over which the tape F is drawn, forms a rest there- 100

for, and is rotated as the tape is drawn over it, and said rest is arranged in close proximity to the tip of the wick-tube B, and preferably at about the same height, as seen in Fig. 1.

5 In lieu of the rotary rest, a stationary rest might be used.

I designates a stationary igniter, which projects in the path of the tape F in such close proximity thereto that the pellets c on the tape 10 cannot pass the igniter as the tape is fed or drawn forward, but bear upon and are ignited or fired by frictional contact with the igniter. The igniter I is elastic, so that it may be first deflected slightly by a pellet bearing against 15 it, and will then be carried suddenly backward to its normal position by its resilience, and scratching quickly across the pellet is sure to fire it. The igniter I consists of a piece of wire coiled at d to give it the desirable elasticity, 20 and attached to the cone C or to the standard D.

It will be seen that the pellets are fired while the tape F is moving toward the wick-tube B, and as there is nothing interposed the fire or 25 flame from the pellet is directed over the wick-tube, thus rendering the igniting of the wick certain.

It will also be observed that the spent tape, after the pellets are ignited, is not consumed 30 or scattered about, but is wound upon the feed-spindle or reel H, and when the roll of tape is entirely exhausted it may be taken off the feed-spindle or reel, and a fresh roll inserted in the magazine.

35 Though only shown in connection with a lamp-burner, the rest for the tape and the stationary igniter are applicable to various forms of igniting mechanism in which tape provided with pellets is employed—such, for instance, as 40 mechanism for igniting gas-burners.

What I claim as my invention, and desire to secure by Letters Patent, is—

1. The combination of a rest over which a tape provided with pellets of ignitable material may be drawn or moved, and a stationary 45

igniter adjacent to the rest, and adapted to bear upon the tape as the latter is drawn or moved over the rest, and serving to scratch and ignite the pellets as they move past it, substantially as specified. 50

2. The combination, with a rest over which a tape provided with pellets of ignitable material may be drawn or moved, of an elastic stationary igniter adapted to be deflected by the pellets upon said tape as in their movement they come in contact with it, and on attaining a certain tension to spring back and ignite them, substantially as specified. 55

3. The combination, with a lamp-burner, of a rest over which a tape provided with pellets of ignitable material may be drawn, a standard or frame supporting said rest and projecting upward within the cone of the burner, but isolated from and independent of the wick-tube, and an igniter adjacent to said rest, and 60 past which said tape is drawn or moved, substantially as specified. 65

4. The combination, with a lamp-burner, of a rest over which a tape provided with pellets of ignitable material may be drawn, a standard or frame supporting said rest projecting upward within the cone, and provided with a catch for holding said cone down, and an igniter adjacent to the tip of the wick-tube, and past which said tape is drawn or moved, 70 substantially as specified. 75

5. The combination, with a lamp-burner, of a rest adjacent to the tip of the wick-tube over which a tape provided with pellets of ignitable material may be drawn, an igniter adjacent to said rest, a magazine attached to the exterior of the burner for containing a roll of tape, and a feed-spindle or reel for drawing said tape from said magazine over said rest and rolling up the spent tape, substantially 80 as specified. 85
